DIVIDED STREAM ELECTRON MULTIPLIER

Richard L. Snyder, Glassboro, N. J., assignor, by
mesne assignments, to Farnsworth Television
& Radio Corporation, Dover, Del., a corpora-
tion of Delaware

Application April 30, 1937, Serial No. 139,949

4 Claims. (Cl. 250—27)

My invention relates to electron multipliers, and more particularly to an electron multiplier wherein the electron stream is divided.

Among the objects of my invention are: To provide an electron multiplier wherein electrons are separated into two divergent streams in order to reduce space charge effects; to provide an electron multiplier of symmetrical structure; to provide an electron multiplier having a shielded input; to provide a means and method of electron multiplication to the end that space charge limitations are reduced; and to provide a simple and efficient means and method of electron multiplication.

My invention possesses numerous other objects and features of advantage, some of which, together with the foregoing, will be set forth in the following description of specific apparatus embodying and utilizing my novel method. It is therefore to be understood that my method is applicable to other apparatus, and that I do not limit myself, in any way, to the apparatus of the present application, as I may adopt various other apparatus embodiments, utilizing the method, within the scope of the appended claims.

In the drawing:

Figure 1 is a longitudinal sectional view showing one preferred embodiment of my invention.

Figure 2 is a circuit diagram showing one way in which the tube of Figure 1 may be connected for operation.

It is obvious that in all electron multipliers wherein electrons are serially directed against a plurality of surfaces capable of emitting secondary electrons at a ratio greater than unity upon electron impact therewith, that as the electrons progress from surface to surface the space between the electrodes of higher potential becomes crowded with electrons until space charge limitations prevent further multiplication. I have found that such limitations may be greatly reduced by dividing the electrons, preferably after the first secondary producing impact, into separate streams, and thereafter separately multiplying each stream. After the proper amount of multiplication has been secured the two streams may be separately collected and recombined in a single work circuit, or, if desired, utilized for different purposes. Each electron path therefore carries only one-half the total current of the device, and therefore the device will not be subject to space charge limitation as soon as if all the multiplied electrons were traveling the same general paths. One apparatus embodying my new method is illustrated herein.

In Figure 1 an envelope 1 is provided at one end with a reentrant stem 2 carrying an input assembly including a thermionic cathode 3 heated by a heater filament 4. Emission from the thermionic cathode 3 is controlled by a control grid 5, and the control grid 5 is surrounded by shield grid 6.

A multiplying assembly is supported by a band 7 clamped to stem 2 by upright risers 8. This assembly comprises a tubular cathode 9, having its inner surface sensitized to produce secondary electrons at a ratio greater than unity. This sensitization may take many forms, but for high emission ratios may be caesium on silver oxide. Tubular cathode 9 has a plurality of support extensions 10 adjacent each end thereof, sealed in glass beads 11. Also sealed to glass beads at each end of the open tubular cathode 9 are support extensions 12 of a pair of apertured collecting electrodes 14, one electrode extending across one end of the tubular cathode and the other extending across the opposite end. Immediately back of each apertured collecting electrode is a disc cathode 15 sensitized as the tubular cathode, also provided with support extensions 16 extending into beads 11. Thus, the tubular cathode, the collecting electrode, and the disc cathodes are locked in relative position by beads 11. The two collecting electrodes 14 are connected together by conductor link 20 and the two disc cathodes are connected together by connecting link 21. Outside connection is made to the combined collecting electrodes through output lead 22 sealed through a stem 23 at the upper end of the envelope, and a disc cathode lead 24 is sealed through the same stem.

At one end of the cylinder, the appropriate electrode 14 and the adjacent disc cathode 15 are provided with central apertures 25 through which leads 26 to the input assembly may pass, thus positioning the input assembly co-axially with respect to the tubular cathode 9.

In operation the device may be operated in one manner as shown in Figure 2. Here the heating source for heater filament 4 is not shown, but the connections thereto are well known to those skilled in the art. The thermionic cathode 3 is connected to ground through lead 30. Input grid 5 is supplied with signal energy from input lead 31. Screen grid 6 is provided with a positive potential from source 32 through lead 34. The tubular cathode 9 is still more positively energized by additional source 35 through lead 36. The two disc cathodes 15 are energized to a still higher positive potential by additional source 35.

37 through lead 39, and output electrodes 14 are held still higher in potential by final source 40 connected to the output electrodes 14 through output resistor 41, the output of the device being made available in a work circuit through output lead 42. If separate output circuits are desired for each collecting electrode, separate leads are brought out to source 40 and an output resistor is placed in each lead.

10 In operation, electrons are emitted from cathode 3, and are accelerated through the grids to impact the interior surface of the tubular electrode. Upon hitting the interior surface of the tubular cathode secondary electrons are emitted 15 at a ratio greater than unity, and this stream of secondaries divides. Those secondaries near the open ends of the tubular electrode are accelerated out through the adjacent ends and through the apertured collecting electrode to impact the 20 disc cathodes 15 and thereby generate more secondaries which are collected by the adjacent collecting electrodes. The electrons impacting the tubular electrode near the center thereof may go in either direction, as shown by electron path 25 line 44 in Figure 2. By thus separating the secondaries produced in the interior of the tubular electrode I greatly reduce space charge effects in the succeeding multiplying stages.

It is obvious, however, that while I have shown 30 only one additional multiplying stage following the tubular cathode, that any number of stages may be operated utilizing the electrons leaving opposite ends of the tubular cathode 9, and any of the well known series of multiplying surfaces 35 may be utilized thereafter.

Such variations in the practice of my new method, and in apparatus equivalents will be immediately apparent to those skilled in the art, and will be deemed to fall within the scope of the appended claims.

40 I claim:

1. An electron multiplier comprising an envelope containing a tubular cathode capable of emitting secondary electrons at a ratio greater than unity upon electron impact therewith and 45 having open ends, an apertured electrode adjacent and extending across each open end, a sec-

ondary emissive cathode back of and parallel to each apertured electrode, said tubular cathode, secondary emissive cathodes and apertured electrodes being energized in the order recited to increasingly higher potentials, and means for liberating primary electrons along the axis of said tubular cathode. 5

2. An electron multiplier comprising an envelope containing a source of electrons, means for modulating electrons from said source in accordance with desired signals, an electrode having a surface capable of emitting secondary electrons at a ratio greater than unity upon electron impact therewith, means for directing modulated electrons from said source against said electrode to produce secondary electrons, means for continuously dividing said secondary electrons into streams sufficiently separate to prevent reaction one upon the other, a secondary electron emitting intermediate electrode in the path of each of said substantially equal streams, means for collecting the secondary electrons emitted from each of said intermediate electrodes, and a single work circuit connected to utilize all of the collected electrons. 25

3. An electron multiplier comprising an envelope containing a hollow open ended cathode having the interior surface thereof capable of emitting secondary electrons at a ratio greater than unity upon electron impact therewith, 30 means for liberating primary electrons along the axis of said cathode, and means for accelerating secondary electrons produced by primary electron impact with the interior surface of said cathode simultaneously out of both ends of said cathode. 35

4. An electron multiplier comprising an envelope containing a hollow open ended cathode having the interior surface thereof capable of emitting secondary electrons at a ratio greater than unity upon electron impact therewith, 40 means for liberating primary electrons along the axis of said cathode, and means for accelerating secondary electrons produced by primary electron impact with the interior surface of said cathode simultaneously out of both ends of said cathode, in substantially equal amounts. 45
